UNITED STATES PATENT OFFICE.

CLELAND COLDWELL ROSS, OF NEWBURGH, NEW YORK.

STATIONARY KNIFE FOR LAWN-MOWERS.

1,355,509.

Specification of Letters Patent. Patented Oct. 12, 1920.

Application filed December 8, 1919. Serial No. 343,344.

To all whom it may concern:

Be it known that I, CLELAND COLDWELL Ross, a citizen of the United States, residing at Newburgh, in the county of Orange and 5 State of New York, have invented certain new and useful Improvements in Stationary Knives for Lawn-Mowers; and I do hereby declare the following to be a full, clear, and exact description of the invention, such as will enable others skilled in the art to which it appertains to make and use the same.

My invention consists in the novel features hereinafter described, reference being 15 had to the accompanying drawings which illustrate one embodiment of my invention, selected by me for purposes of illustration, and the said invention is fully disclosed in the following description and 20 claims. My invention relates particularly to the stationary knife or blade of a lawn mowing machine. These stationary knives, as ordinarily constructed, comprise a cast or malleable iron knife bar extending transversely across the machine and carrying the 25 stationary blade or cutter, which is usually a flat thin piece of steel secured by means of rivets or screws to the knife bar, and maintained by the knife bar in proper relation 30 to the rotary cutter of the machine. In using stationary knives of this character, it is found that they frequently become bent or chipped between their ends so that the cutting edge is no longer straight, and 35 therefore does not coöperate accurately throughout its entire length with the spiral blades of the rotary cutter or "wiper." This chipping, bending, or deflection of the stationary blade occurs more frequently in 40 machines for cutting a comparatively wide swath such as high-class hand machines, horse mowers, and motor mowers. It has been proposed, for the purpose of remedying this difficulty to form the stationary 45 blade of wrought metal in the form of a channel, the angular flanges of the channel serving to stiffen the blade structure and prevent its bending, while at the same time providing two cutting edges, so that the 50 blade may be reversed with respect to the knife bar when one of its cutting edges has become seriously worn. This channel knife is covered by Letters Patent granted to 55 William H. Coldwell #817,157, dated April 10, 1906.

While this channel knife is very satisfac-

tory in use, it is expensive to manufacture, and its use has been limited to a large extent, on that account, to lawn mowers of the higher grades, and more expensive types 60 such as the higher priced hand lawn mowers, and mowers operated by horse and by motors.

The object of my invention is to provide a channel knife which will obtain the advantages of the structure disclosed in the Coldwell patent above referred to, but which can be much more cheaply manufactured, so that the advantages of the channel knife bar can be extended to the cheaper 70 grades of lawn mowers, and for the purpose of effecting greater economy in the use and manufacture of all types of lawn mowers in which a channel knife bar can be employed.

In the accompanying drawing, which illustrates one form in which I have contemplated embodying my invention, and which I have selected for the purpose of illustrating the same,

Figure 1 represents a side elevation of a hand lawn mower having my invention embodied therein, a portion of one of the side frames being broken away for the purpose of showing the knife bar and cutting 85 blade which are illustrated in section.

Fig. 2 is a perspective view of the knife bar and cutting blade secured thereto, detached from the machine.

Fig. 3 is a transverse sectional view of 90 the knife bar and cutting blade.

Fig. 4 is an enlarged detail section of the body portion of the blade showing the manner in which it is shaped for the reception of the cutting edge sections.

Fig. 5 is an enlarged detail section of the completed blade.

Referring to the accompanying drawing in which I have illustrated my invention applied to a lawn mower, 1 represents the 100 driving wheels which transmit power to the rotary cutter, indicated at 2, and provided with the usual spiral knife blade 3, the rear end of the mower being supported upon the usual adjustable ground roller 4, and the 105 mower being movable in the direction of the arrow in Fig. 1. The specific construction of these parts and the driving gearing for the rotary cutter have no bearing on my present invention, and they will not be further illustrated or described.

5 represents the knife bar which may be

of any usual or desired construction. I prefer to form it in the manner herein shown, and to provide it on its bottom face with a pair of ribs 6—6 extending longitudinally of the bar and separated by a recess, indicated at 7, so that in machining these bars for the reception of the blade, it is only necessary to plane the bottom faces of the ribs. The bar 5 is provided at each end with means for attaching it to the side frames of the mower, and I prefer to attach the bar pivotally to the mower frames, and to provide means for adjusting the bar and the knife carried thereby, around the axis 15 of such pivotal connection, as is customary in lawn mower construction. To this end the knife bar is provided at each end with an attaching lug 8 having an aperture 9 therein for the passage of a pivot bolt 10 which secures it to the adjacent side frame of the mower, and each attaching lug is provided in this instance on each side of the central aperture 9 with a shoulder 11, said shoulders being acted upon by set screws, indicated at 12—12 in Fig. 1, which pass through lugs on the side frames, and engage said shoulders so as to hold the knife bar in its adjusted position. It is obvious that by loosening one of these screws 12 and 20 tightening the other, the knife bar can be rocked upon its pivotal axis, being the axis of the bolts 10, thus raising or lowering the front edge of the cutting blade hereinafter described.

35 In the formation of my improved cutting blade I form a body portion 13 which is shown in detail in Fig. 4, and which is provided with a flat central portion, having at each edge an upwardly extending lip, indicated at 14. This portion is formed of wrought metal, preferably wrought iron or soft steel, and may be made of comparatively inexpensive and low grade material, as it is not required to be tempered. The body 40 portion of the knife is formed by rolling machining, or in any other desired manner, in the shape or form illustrated in Fig. 4, and provides at each edge a longitudinal recess 15 having an upwardly and outwardly inclined bottom face 16, and a shoulder 17 at its inner edge, which shoulder is preferably perpendicular to the inclined bottom face 16 of the recess. The lower faces of the lips 4 are preferably inclined, as indicated at 18, 45 and are substantially parallel with the upper faces 16. These bars may be rolled in any desired lengths and cut off in sections to form knife bar bodies of different lengths according to the requirements of the lawn 50 mowers with which such knives are to be used. Knives are completed by fitting into the recesses 15—15 strips or edge pieces 19 of steel of good quality, capable of being hardened, and producing a serviceable cutting edge. These strips are seated in the re-

cesses 15—15 with their inner edges abutting against the shoulders 17—17 and their outer edges extending perpendicularly to the plane of the central portion of the main body, thus forming an acute angle cutting edge, indicated at 20, the upper face of which is inclined sharply upward. The edge portions 19 of the knife are secured to the main body 13 preferably so as to form an integral structure therewith. This is accomplished 70 by welding the edge pieces 19 to the body portion of the knife, and this is my preferred construction. They may be secured by brazing, riveting, or otherwise, but I prefer to weld these strips to the knife bar. 75

It will be noted that the resulting knife is of substantially channel shape. The edge portions are hardened in any usual or desired manner, and the resulting structure therefore produces a channel bar having 80 hardened upwardly inclined cutting edges which impart great stiffness and rigidity to the knife blade, while enabling it to be manufactured more cheaply than where the entire knife is formed of high grade steel. 90 My improved knife is secured in any usual or desired manner to the bottom of the knife bar 5, preferably in engagement with the lower faces of the ribs 6—6 thereof. In this instance I have shown the central portion 95 13 of the knife blade provided with screw holes, one of which is indicated at 21, to receive a retaining screw 22 extending into threaded apertures in the knife bar, and this is a convenient manner of attaching the 100 knife bar to the knife. It will be noted, by reference to Fig. 3, in which the sweep of the cutting edges of the rotary cutter is indicated by the dotted line 23, that when the knife is in adjusted position, one of the acute 105 angular edges 20 is presented to the spiral cutting edges of the rotary cutter in such a manner that the upper face of the cutting portion of the blade extends downwardly and rearwardly away from the path of the 110 rotary cutting blades, so that as the cutting edge 20 wears, the portion which frictionally engages the rotary cutting blades will be very small even when the knife has been considerably worn, thus enabling the cutting 115 edge to be used for a long time without materially increasing the frictional resistance and wear on the coöperating cutting blades, which results where the upper face of the cutting edge of the stationary knife is substantially horizontal. When one of the cutting edges has been worn away, it is only necessary to detach the knife blade, and reverse it to present the other cutting edge 20, and thus secure a fresh and unworn cutting 120 edge. By my improved construction I am enabled to obtain the advantages of the channel knife bar construction, while greatly reducing the cost of manufacture. In addition to cheapness of manufacture, my im- 130

proved channel knife is in fact, by reason of the co-action of the hardened edges, welded or otherwise secured in the shouldered recesses, at the edges of the knife body, more rigid than a channel knife formed by rolling the stock with upturned edges, and less liable to chip, and is more durable.

In forming the body of the knife I have stated that it may be rolled from stock in suitable lengths. I may also in some instances find it desirable to form this knife body from ordinary rectangular rolled stock of the form indicated in dotted lines in Fig. 4, in which case the recesses 15—15 and the angular bottom faces 18 of the lip 14 may be machined by milling or planing portions to form the lips 14, the cutting edge pieces 19 being welded or otherwise secured in the recess 15, in the manner hereinbefore described.

What I claim and desire to secure by Letters Patent is:—

1. A stationary knife for lawn mowers, comprising a main body consisting of a flat sheet of wrought metal of substantially uniform thickness throughout its main portions, and provided along a longitudinal edge, with an upwardly extending inclined lip of less thickness than the main portion of the blade, and a tempered cutting edge portion united to said lip and the adjacent portions of the main body, said edge portion lying upon the upper face of said lip and being provided with a cutting edge at the upper edge of its outer face, located above said lip and above the plane of the main portion of the main body of the knife.

2. A stationary knife for lawn mowers comprising a main body consisting of a flat sheet of wrought metal, the central longitudinal portion of which is of substantially uniform thickness, and provided along its opposite longitudinal edges with upwardly extending oppositely inclined lips of less thickness than the central portion of the main body, and forming a longitudinal recess on the upper side of each lip terminating at its inner edge in a shoulder, and a cutting edge portion of tempered steel located in each of said recesses on the upper faces of said lips and engaging said shoulders, and united to the main body to reinforce and stiffen the same, said edge

portions being inclined upwardly in opposite directions, and each provided at the upper edge of its outer face with an acute angular cutting edge located above the plane of the upper face of the central portion of the main body.

3. A stationary knife for lawn mowers comprising a main body consisting of a flat sheet of wrought metal having its central longitudinal portion of substantially uniform thickness and provided along its opposite longitudinal edges with upwardly extending oppositely inclined lips of less thickness than the central portion of the main body, each lip having its outer face substantially perpendicular to the plane of the central portion of the main body, and the upper edge of said face substantially in the plane of the upper face of said central portion, an angular recess being formed above each of said lips terminating at the inner edge in an angular shoulder, and separately formed cutting portions of hardened steel welded to the main body, and lying in said recesses, said cutting portions being inclined upwardly in opposite directions, and each having its inner edge in engagement with one of said shoulders and its exterior face in alignment with the exterior face of the adjacent lip, the upper edges of said exterior faces of the said cutting portions forming acute angular cutting edges to engage the blades of the rotary cutter.

4. In a lawn mower, the combination with a main frame, a rotary cutter mounted therein, and a stationary knife bar secured to said main frame, of a stationary knife consisting of a flat sheet of wrought metal, the central longitudinal portion thereof being of uniform thickness and provided with means for detachably connecting it to the knife bar, said main body being provided along its longitudinal edges with upwardly extending oppositely inclined lips having their upper faces located below the plane of the central portion, and edge strips of hardened steel of substantially uniform thickness throughout secured upon said lips and maintained in oppositely inclined positions, and provided at their outer faces with acute angular sharpened cutting edges.

In testimony whereof I affix my signature. 105
CLELAND COLDWELL ROSS.
